UNITED STATES PATENT OFFICE.

HAZAELE WEST, OF WASHINGTON, DISTRICT OF COLUMBIA.

TYPEWRITER-LINE GUIDE.

Application filed July 28, 1923. Serial No. 654,447.

To all whom it may concern:

Be it known that I, HAZAELE WEST, a citizen of the United States, residing at Washington, in the District of Columbia, 5 have invented certain new and useful Improvements in Typewriter-Line Guides; and I do hereby declare the following to be a full, clear, and exact description of the invention, such as will enable others skilled 10 in the art to which it appertains to make and use the same.

The present invention relates to improvements in typewriter line guides particularly useful in conjunction with typewriters, such 15 as the Underwood, in which the case-shift frame shifts upwardly from a normal position whenever capital letters are to be typed.

An object of the invention is to eliminate the highly objectionable defect in present 20 models of typewriters using a case-shift frame that lifts when shifting, but provided with a line guide that is rigid with the under frame of the machine, and so, not capable of moving upward with the rising case-shift 25 frame on shifting. The difficulty experienced in the use of that type of machine is that, on attempting to type near the bottom of the page, that is, after the sheet has left the under-side feed rolls, it is practically 30 impossible to shift without the sheet being pulled above the stationary line guide. Consequently, when the shift is released and the case-shift frame descends, the bottom of the sheet hangs on the line guide and is pulled 35 out of alignment and often entirely out of range of the type, so that the sheet must be removed from the machine before finished.

It is another object of the invention to provide a line guide that is movable with 40 the case-shift frame and that bears a constant fixed relation to the platen and is adapted to be shifted with the platen and case-shift frame without changing the relation of the paper thereto or affording the 45 possibility of the lower edge of the paper getting above the line guide when the shift occurs.

It is a further object of the invention to provide a line guide in a similar mechanical form at relatively small cost suitable for 50 attachment to existing machines without requiring alteration and equally adaptable for initial installation upon factory made typewriters, such line guide being formed in one or more pieces of metal or other appropriate 55 material and being constructed to avoid any binding action upon the platen.

With the foregoing and other objects in view the invention will be described more particularly hereinafter in conjunction with 60 the accompanying drawings and the features of novelty will be pointed out distinctly in the appended claim.

In the drawings wherein like parts are denoted by like symbols throughout the several views,

Figure 1 is a fragmentary perspective view of portions of an Underwood typewriter frame and carriage including the shaft mechanism and showing the invention applied thereto.

Figure 2 is a vertical section taken transversely through the same and showing the carriage in the normal low position.

Figure 3 is a similar view with the carriage raised.

Figure 4 is a perspective view of the improved line guide, and

Figure 5 is a similar view showing a slight modification.

Referring more particularly to the drawings, 6 designates generally the carriage of an Underwood typewriter mounted in the customary way in the frame which is shown partially at 7. The carriage 6 is provided with the platen 8 over which the sheet of paper 9 travels. The shift key bars are represented at 10 and they pivot upon a rod 11 carried in a well understood manner by the under frame of the machine which has 90 been omitted for clearness in illustration. The shift key bars 10 are provided with upwardly extending arms 12 positioned and disposed to engage behind the frame ends

- or brackets 13 of the platen shifting frame, said frame ends or brackets being pivoted upon the frame and hinging about rods 14. These frame ends or brackets 13 are connected to the typewriter case-shift frame for lifting the same and by a comparison of Figures 2 and 3 it will be made clear as to the relative positions of the parts in the normal and raised positions of the carriage.
- Now in accordance with existing constructions in typewriters of this kind, the line guide which is designated at 15 is mounted fixedly and immovably upon the under frame of the typewriter and it does not partake of the movement of the case-shift frame. Consequently when a sheet of paper such as indicated at 9 in Figure 1 arrives at the position illustrated with its lower edge just beneath the line guide 15, any shifting of the case will bring the paper edge above the top edge of the line guide where it will catch on the following descent of the case-shift frame.
- To avoid this the present invention aims to mount the line guide 15 upon a portion of the elevating mechanisms for the case-shift frame to cause such line guide to participate in the shifting movement of the case-shift frame whereby its relation to the platen 8 and to the paper 9 wound about it will at all times remain constant and fixed irrespective of the position of the platen.
- To accomplish this the line guide is preferably made in the form shown in Figure 4 in which such line guide is shown to be made generally after the same design and shape as at present used employing the wings 16 and 17 at opposite sides of the central type slot 18 through which the type enters to make the impression upon paper. The wings stand up from the transverse bar which forms the body of the line guide and these wings may be provided with straight or sloping upper edges or a combination of both as shown in the drawings. The line guide in the instance shown extends laterally in the form of flanges 19, which flanges extend out to a position substantially in front of the frame ends or brackets 13 and the flanges extend downwardly and are preferably of considerable width affording the necessary amount of material to impart rigidity and strength to the line guide and to the supporting arms 20 of the line guide, connected with the lower relatively wide edges of the flanges 19.
- The arms 20 are curved downwardly and rearwardly from the flanges and are preferably bifurcated at their lower rear ends as indicated at 21 to enable the same to straddle the frame ends or brackets 13 to which said arms are secured as by the pins or bolts 22, it being understood that a rigid connection is made between these two parts to positively shift the line guide with the brackets. Now the arms 20 may be made in one piece with the line guide and with the flanges 19 and commercially the entire line guide and its supporting means will probably be stamped out of sheet metal which will thereupon be bent in the shape shown and described. The lower edge of the line guide is adapted to fit in the lower position of the case-shift frame upon a portion of the under frame upon which it accurately seats, the space provided by the downwardly offset parts 23 of the typewriter frame is taken advantage of to receive the downwardly extending portion of the flanges 19 and the arms 20 are so bent as to pass about its downwardly offset frame portions and to avoid contact or interference with other parts of the mechanism. The wings 16 and 17 are of course provided with the scale in accordance with the usual practice.
- Now in Figure 5 the wings 16^a and 16^b are made separately from the line guide bar 15 and these wings are pivoted to the bar as indicated at 24, there being coil or other springs 25 associated with the pivot joints in order to yieldingly urge the wings against the platen 8. In this form the line guide or its wings will exert a pressure upon the paper 9 and the spring and pivoted character of the wings enables them to yield forwardly when the case is shifted so as to avoid any binding against the platen. The springs constantly maintain a tension upon the sheets of paper upon the platen and this acts to silence the sound ordinarily produced by the action of the type in striking the paper, particularly if the paper is held loosely upon the platen which is common with the present form of line guide and paper feed rollers.
- The body of the line guide in this case is made substantially in accordance with the construction previously described in conjunction with Figure 4 although it is to be understood that modifications in the shape, size and proportion of the various parts may be resorted to in making the improvement applicable to typewriters of various makes.
- It will be appreciated that with the line guide so constructed and carried that the paper will be effectually prevented from escaping over the paper edge of the line guide and the position of the paper will be constantly preserved and held intact without regard to the position of the case-shift frame until the paper by the ordinary feeding mechanism is finally released from the platen. It will be found that not only the last two or three lines upon the paper sheet may be typed with regularity and correct alignment but that the typing of a last line directly contiguous to the bottom edge of the sheet may be carried out with as much

regularity and with as good alinement as lines made in the body of the sheet.

What is claimed is:—

In a typewriter having an under frame,
a case-shift frame thereon, a platen mounted in the case-shift frame, pivoted brackets in the under frame coupled to the case-shift frame and acted on by the shift keys, a line

guide comprising a body bar, wings pivotally mounted on said bar and spring pressed toward the platen, and said bar extending to the sides of the machine and provided with downwardly extending lugs, and curved arms secured to said lugs and extending to the pivoted brackets.

HAZAELE WEST.
